UNITED STATES PATENT OFFICE.

JOHAN RICHARD FROBERG, OF GRASS VALLEY, CALIFORNIA, ASSIGNOR OF
TWO-THIRDS TO CHARLES E. CLINCH AND ABE HALL, OF SAME PLACE.

HEATER.

SPECIFICATION forming part of Letters Patent No. 639,550, dated December 19, 1899.

Application filed June 21, 1899. Serial No. 721,337. (No model.)

To all whom it may concern:

Be it known that I, JOHAN RICHARD FROBERG, a citizen of the United States, residing at Grass Valley, in the county of Nevada and 5 State of California, have invented certain new and useful Improvements in Heaters, of which the following is a specification.

My invention relates to heaters, and particularly to lunch-bucket heaters, and has for 10 its object to provide a simple, cheap, and easily carried and operated detachable and adjustable heater for lunch-buckets and like utensils. This object I accomplish in the manner and by the means hereinafter more fully 15 described in detail, and particularly pointed out in the claims, reference being had to the accompanying drawings, in which like reference-letters indicate like parts in all the figures.

20 Figure 1 is a front view of my invention with bucket. Fig. 2 is a side view of same. Fig. 3 is a plan view of same with bucket removed.

A represents an ordinary lunch-bucket.

25 My invention consists of a rectangular base B, formed of a single wire, which is turned into loops b at each corner and has its ends fastened together. A double candlestick C, formed of a single wire wound in coils to form 30 the sockets c and having its ends bent into hooks c' over one side of the base B and provided with a plate c², one edge of which is secured around the wire between the sockets c and the other edge of which is hooked over 35 the other side of the base B and slides along said base B. At each end of the base B is a rectangular arm D, formed of a single wire turned into an eye d in the center of the upper end of the arm D and having its two ends 40 hooked into the loops b at the corners of the base B. An arm E, formed of a single wire, the lower end of which is formed into a loop e, sliding on the sides of the arm D, and which passes through the eye d and has its upper 45 end formed into a hook e', to hang the whole on the handle of the bucket A, slides on each arm D.

When not in use, the arms E are slid down along the arms D, the arms D folded down on 50 the base B, one on top of the other, reducing the device to a small compact package easily

carried. When it is desired to use the heater, the arms D are turned up at right angles to the base B, the arms E extended sufficiently to allow the hooks e' to grasp the handle of 55 the bucket A, one on each side, the base B being at a suitable distance below the bucket A, and the candles lighted, the candlestick C being moved along the base B as desired.

I do not confine myself to the use of wire 60 or the particular construction described, nor to the use of candles; but any suitable material may be used. The base may be solid, with a longitudinal recess or slot in which a receptacle containing any form of the usual combustible material may slide, and the arms may be hinged to the ends of the base in any way and themselves may be differently shaped, and the sliding arm may be differently arranged.

70 The features of my invention are a base, a receptacle containing the combustible material and adjustable along such base, arms which may be folded down one over the other on such base, and extensible arms on such 75 folding arms.

Having thus described my invention, what I claim as new, and desire to secure by Letters Patent, is—

1. In a lunch-bucket heater, a rectangular 80 base formed of a single wire with eyes turned in it at each corner, rectangular wire arms hooked in said eyes and having an eye in the center of the closed upper end, wire arms passing through the eyes in the ends of said rectangular arms, and having loops at their lower ends adapted to slide on said rectangular arms and hooks at their upper ends adapted to engage the handle of said bucket, substantially as shown and described.

85 90 95 2. In a lunch-bucket heater provided with a base having a longitudinal opening in its center, a double candlestick formed of a wire coiled to form sockets and having its ends hooked over one side of the base and provided with a plate hooked over the other side of the base, substantially as shown and described.

3. A lunch-bucket heater consisting of a rectangular base formed of a single wire with eyes turned in it at each corner, rectangular 100 wire arms hooked in said eyes and having an eye in the center of the closed upper end, wire

arms passing through the eyes in the ends of said rectangular arms, and having loops at their lower ends adapted to slide on said rectangular arms and hooks at their upper ends 5 adapted to engage the handle of said bucket, and a double candlestick formed of a wire coiled to form the sockets and having its ends hooked over one side of the base and provided

with a plate hooked over the other side of the base, substantially as shown and described. 10

In testimony whereof I hereto affix my signature in the presence of two witnesses.

JOHAN RICHARD FROBERG.
